UNITED STATES PATENT OFFICE.

JOHN N. REYNOLDS, OF GREENWICH, CONNECTICUT, ASSIGNOR TO WESTERN ELECTRIC COMPANY, OF NEW YORK, N. Y., A CORPORATION OF ILLINOIS.

TEST-GUARD FOR AUTOMATIC SWITCHING APPARATUS.

1,124,060.

Specification of Letters Patent.

Patented Jan. 5, 1915.

Application filed August 18, 1913. Serial No. 785,884.

To all whom it may concern:

Be it known that I, JOHN N. REYNOLDS, a citizen of the United States, residing at Greenwich, in the county of Fairfield and 5 State of Connecticut, have invented a certain new and useful Improvement in Test Guards for Automatic Switching Apparatus, of which the following is a full, clear, concise, and exact description.

10 This invention relates to telephone exchange systems of the automatic and semi-automatic type in which the selection of lines or trunks for the extension of telephone circuits is accomplished by mechanical selector switches and means whereby a plurality or group of such switches may be driven from a common source of power or master mechanism.

15 The principal feature of this invention 20 resides in means whereby each line will be caused to test busy while in use, and whereby all lines of a group will be caused to test busy during the period that the master mechanism is in use.

25 The drawing is a diagrammatic illustration of the apparatus and circuits comprising my invention.

The mechanism shown in the drawing is substantially the same as that disclosed in 30 Patent No. 1,020,185. It is of the master and individual type of mechanism arranged to be operated on what is known as the panel form of selector multiple. This multiple consists preferably of strips of metal 35 having contact points spaced at regular intervals along their entire length. These strips are placed one upon another with strips of insulating material between in such a manner as to form vertical banks of 40 contacts over which the selector contact brushes can be moved in a vertical direction, each vertical bank of contacts forming the co-operating terminals of a separate selector. The banks may comprise any de- 45 sired number of sets of contacts and the selector multiple may comprise as many multiple banks as may be conveniently used. As herein described, each bank is considered as accommodating contacts forming the 50 transmission and test terminals of 100 lines, but it should be understood that this invention is not limited to such construction.

In the drawings a part of a bank of contacts as referred to above is indicated gen-

erally at 84. The set of contacts 85, 86 and 55 87 form, respectively, the transmission and test terminals of the line 357, 355 and 356 to a further selector. The brush carrier 88 carries the brushes 89 and 90 arranged to contact respectively with the terminals 85 60 and 86, and the brushes 91 arranged to contact with the test terminal 87. This brush carrier is carried by a metallic tape 92, passing around the sheave 76 of the driving mechanism individual to the selector and an 65 idler pulley 8 at the top of the bank of terminals. This tape when moved by the rotation of the sheave 76 carries the brushes into position to make contact with the terminals 85, 86 and 87 of the desired line, the selection being determined by the extent of the movement of the tape, the control of which will be hereinafter fully set forth.

Briefly considered, selection is accomplished by moving the brushes to the top of 75 a group of terminals and then causing the brush carrier to be moved in the reverse direction step by step over the sets of contact terminals until the desired set has been reached.

80 The driving mechanism through which power is supplied for moving the brushes 89, 90 and 91 on the brush carrier 88 into contact with the terminals 85, 86 and 87 comprises the master clutch mechanism 13 85 common to a plurality of selectors, and the individual mechanism 14 individual to a single switching apparatus.

Master driving mechanism.—The master clutch 13 comprises a shaft 15 to one end of 90 which is attached the disk 19 and to the other end of which is attached the power wheel 20. Adjacent to the disk 19 is a disk 23 of magnetic material fixed to the pinion 22 by means of the rotatable sleeve 21. 95 This sleeve 21 is free for longitudinal movement and upon energization of the electromagnet 25, the disk 23 will be drawn into frictional engagement with the disk 19, whereby power will be transmitted to the 100 pinion 22. The pinion 22 meshes with the wheel 28 fixed upon the shaft 29. Upon the shaft 29 are also mounted the interrupters 33 and 34. The interrupter 33 co-operates with the contacts 35, 36 and serves to make 105 and break the circuit between these contacts once for every revolution of the shaft 29. The commutator 34 similarly co-operates

with the contacts 37, 38 to make and break the circuit between these contacts at each revolution of the shaft 29. The relation of the make and break of the circuits between contacts 35 and 36, 37 and 38, respectively, will be hereinafter referred to.

The disk 39 which is also mounted on the shaft 29 has coöperating therewith the arm 40 mounted upon the shaft 29 and held in definite relation to the disk 39 by the spring 41, which is fastened at its respective ends to the disk and the arm. This arm 40 coöperates with the armature 42 of the stop magnet 43 to stop the rotation of the disk 39 and likewise the shaft 29 when the magnet 43 has been deenergized. It, however, permits a slight overrun by the disk 39 due to the extension of the springs 41, which overrun will be corrected and the disk 39 brought back into proper position by the contraction of the spring 41. The armature 42 which is normally in a retracted position, due to the tension of the retracting spring 46, operates when attracted for purposes hereinafter set forth to close the contacts 47 and 48.

Upon the shaft 29 are fixed at proper intervals the gearwheels 69 which transmit power to the individual driving mechanisms 14.

Individual driving mechanism.—The individual driving mechanism comprises the shaft 70, to one end of which is affixed the gearwheel 71 which meshes with the gearwheel 69, above referred to, upon the main driving shaft 29. Adjacent to the gearwheel 71, and also fixed to the shaft 70, is the disk 72 of soft iron, or other magnetic material, which forms the armature of the electromagnet 73, which when energized attracts the disk 72 to move the shaft 70 so that the clutch member 74 fixed on the other end of the shaft is moved into operative relation with the clutch member 75, fastened to the sheave 76 around which the metallic tape 92 passes. The shaft 70 is normally held in a position in which the clutch member 74 is out of coöperative relation with the clutch member 75 by means of the spring 78.

The inner rim of the sheave 76 is made to form a ratchet by having cut therein the teeth 79. Coöperating with these teeth 79 is the armature 80 of the electromagnet 81, by the energization of which the armature is adapted to be attracted to remove the projecting piece 82 upon the armature 80 out of coöperative relation with the teeth 79. The armature 80 is normally held retracted and the projecting piece held in engagement with the teeth 79 by the spring 83.

The movement of the sheave 76, therefore, depends upon the energization of the clutch magnet 73 and the rotation of the shaft 29. The shaft 29, however, having moved the sheave and tape into any given position,

they may be prevented from returning by the projection 82 upon the armature 80 under the control of the release magnet 81.

Sequence switch.—To control the local circuits at the various parts of the system, which local circuits must be established in definite order at successive stages of the operation, automatic switching appliances which are termed "sequence switches" are employed. A sequence switch 200 is associated with the master driving mechanism and a sequence switch 100 is associated with each individual driving mechanism as is indicated upon the drawings. These sequence switches each consist of a movable switch 75 operating member, a number of circuit-changes being made in sequence as said member is moved from one position to another. An electromagnet and a constantly rotating source of power, the connection of 80 which with the movable member is controlled by said magnet, is provided for advancing said movable member. In each position to which the sequence switch is advanced a set of circuits is established by 85 which a given operation of the device under control is made possible, and at the same time another circuit is prepared whereby the controlling magnet of the sequence switch 90 may be actuated, so that the sequence switch 95 may again be automatically advanced to the next position in which a new set of circuits is established.

In the form of sequence switch mechanism shown diagrammatically on the drawings, 100 171 represents a constantly rotating shaft 105 having at one end a disk 174 of brass or other non-magnetic material. Adjacent to the disk 174 is a disk 176 fixed on the shaft 177 and forming the armature of the clutch magnet 101. This disk 176 is formed of magnetic material. Upon the energization of the electromagnet 101 the disk 176 will be drawn into frictional contact with the disk 174 which is constantly rotating and 110 the two disks will, therefore, rotate together.

Upon the shaft 177 is also fixed a gearwheel 181 which meshes with the gearwheel 182 fixed on a shaft 184. On this shaft 184 115 are fixed cam wheels made of insulation, upon the outer rim of which are formed cam surfaces which coöperate with the various contact springs represented in the drawing, to force such springs into and out of engagement with their coöperating contacts.

Fastened upon one end of the shaft 184 is a stop wheel 190 formed with notches 120 upon its periphery in which the projection 191 upon the armature 192 of the electromagnet 102 is adapted to rest when the armature is retracted to stop the rotation of the shaft promptly and accurately when the position desired has been reached and the electromagnet 102 has been deenergized. 125 130

Associated with the sequence switches 100 and 200 are the special contacts 110 and 210 respectively. These contacts are open only at the positions noted adjacent thereto and therefore determine the only positions in which the sequence switches can stop.

Operation.—In the drawing is shown a master driving mechanism and a single selector 352 associated therewith. It is to be understood, however, that in practice a plurality of selectors would be associated with the common driving shaft 29. This group of selectors will carry the brush terminals of a corresponding group of trunk lines, only one trunk comprising conductors 303 and 304 being here shown.

We will now assume that the calling line has been connected through some well known means with the brushes 366, 367 and 368 of a selector 375 and that this selector is caused in a well known manner to hunt for the terminals of an idle trunk. Associated with terminals 310 and 311 of the trunk conductors are the test terminals 312. Associated with the test terminals 312 of each trunk is a double wound relay G, and the conductors 165 and 166 are common to all the relays G of a group of trunks.

As previously stated, the object of this invention is to provide means whereby all the test terminals of a group of trunks will test busy while the master mechanism is in use, and further means whereby each trunk will test busy while a connection is established or being established thereover.

Assuming now that the brushes 366, 367 and 368 are passing over the terminals of a group of trunks, upon the brush 368 engaging the test contact 312 of the first trunk line, if this trunk line is idle and the master mechanism is not in use, a circuit will be completed from the battery 150, through the resistance R, armature and back contact of the relay G associated with the first test contact 312, brush 368 and test relay T to ground, thus energizing the relay T and causing the selector to stop with the brushes on the terminals of this trunk. If, however, at a preceding instance, another selector 375 had come to rest on the test terminal of one of the trunks of the group, the potential of the test terminals would be reduced, as will presently appear, and insufficient current would flow through the relay T to attract its armature, and the brushes would pass over all the test terminals of the group, unless the master mechanism became idle after having performed its part of setting up the preceding connection before the last test terminal of the group was reached, in which case, those of the group remaining to be passed over will be tested, and if an idle trunk is found, the brushes will come to rest on the terminals thereof. The reason for this will presently appear.

Associated with the conductors, terminating in the brushes 366 and 367 by any desired means are the leads 364, 365 extending to a sender of the revertive impulse type. A circuit will now extend from battery 308, 70 stepping magnet 307, resistance 305, conductor 365, brush 367, conductor 304, sequence switch contact 103 (0), left winding of line relay 314, conductor 303, brush 366 and lead 364 to ground. Relay 314 will not, however, 75 be actuated due to the high resistance of its left winding and to the resistance 305 in the circuit. Upon the attraction of the armature of stop relay 306, resistance 305 is short circuited, increasing the flow of current in the circuit just traced. Relay 314 will now 80 become energized, completing a circuit from battery, through armature and front contact of relay 314, conductor 120, sequence switch contact 104 (0), sequence switch contact 105 85 (0), clutch magnet 101, stop magnet 102 to ground, whereupon the individual sequence switch 100 will move to position 1. In position 1 a circuit is completed from conductor 303, through sequence switch contact 90 106 (1), low resistance right winding of relay 314, sequence switch contact 107 (1); conductor 121, left winding of relay L, sequence switch contact 203 (0), brushes 36 95 and 35 of the interrupter, sequence switch contact 204 (0), conductor 122, sequence switch contact 116 (1) to the other conductor 304 of the trunk line. Relay L will now 100 be energized and in attracting its armature will complete a circuit from battery, through its armature and front contact, sequence switch contact 205 (0), clutch magnet 201, and stop magnet 202 of the master sequence switch 200 to ground. Master sequence switch 200 now moves to position 2 105 under the control of its special contact 210. As the sequence switch 200 reaches position 2, a circuit is completed from battery, through armature and front contact of relay L, sequence switch contact 205 (2), stop magnet 110 115 43 to ground. Magnet 43 becomes energized, removing its armature 42 from engagement with the arm 40. The attraction of the armature 42 also causes engagement of the contacts 47 and 48, completing a circuit from battery, through the master mechanism clutch magnet 25 and conductor 123, causing the shaft 29 and the drum 76 to rotate, the individual clutch magnet having been previously energized through a circuit 120 from battery, through sequence switch contact 111 (1). The gears 69 and 71 are of such proportions that each rotation of the shaft 29 will carry the brushes of the selector over a group of terminals in the bank 125 84. Each revolution of the shaft 29 also causes, by means of the interrupter disk 33 and the brushes 35 and 36, an interruption of the previously traced circuit through relay L, deenergizing the stepping magnet 307 130

and thus causing the sender to take one step for each group of trunks traversed by the brushes. The rotation of the interrupter 34, also attached to the shaft 29, however, closes a circuit to maintain the selecting relay L energized while the above traced circuit is opened, by the closure of a circuit from battery 30, through brushes 37 and 38, metallic portion of the interrupter 34 and the right winding of relay L. Relay 314 remains energized during the periods the circuit through its right winding is interrupted, as the flow of current through the left winding of this relay is sufficient to hold up its armature even though the armature of relay 306 may be retracted, thus including the resistance 305 in the circuit, although insufficient to attract it. The opening of the circuit by the interrupter 33, as just stated, caused the deenergization of the sender stepping relay 307. As the shaft 29 continues to rotate, however, circuit is again completed through the metallic portion of the interrupter 33 to again close the circuit, and upon a slightly further rotation of the shaft, the local energizing circuit of the selector relay L through the right winding thereof is opened by the contacts 37 and 38 engaging the insulated portion of the interrupter disks 34.

If at this stage of the operation the short circuit about resistance 305 remains closed, the rotation of the shaft 29 and the consequent elevation of the brush carrier will be continued until the brushes have passed over another group of terminals. These operations will be repeated and the contact brushes caused to move upwardly over the groups of contact terminals until the repeated energization and deenergization of the sender stepping magnet causes the deenergization of stop relay 306, thus including the resistance 305 in the sender circuit. When now the rotation of the shaft 29 has caused the opening of the local energizing circuit through the right winding of relay L, relay L will become deenergized, due to the inclusion of resistance 305 in its circuit, and its armature retracted, closing a circuit from battery through sequence switch contact 208 (2), clutch magnet 201 and stop magnet 202 of master sequence switch 200, causing the sequence switch to move out of position 2 and back to normal or zero position. As sequence switch 200 moves out of position 2, it momentarily closes sequence switch contact 209, completing a circuit from battery, through contact 209 (2), contact 109 (1), clutch magnet 101 and stop magnet 102 of the individual sequence switch 100, thus moving the sequence switch into position 2. When the sequence switch reaches position 1 $\frac{1}{2}$, a circuit is completed from battery 360, through resistance 359, conductor 356, contact 87, brushes 91, sequence switch contact

114 (1 $\frac{1}{2}$) and test relay J to ground. If the contact 87 is the test terminal of an idle trunk, relay J will be energized and, in attracting its armature, will complete a momentary circuit from battery, through contact 112 (2), armature and front contact of relay J and magnets 101 and 102 of sequence switch 100, and causing said sequence switch to continue to position 3 or talking position. If, however, a selector is associated with the multiple terminals of this trunk, insufficient current will be supplied to relay J to cause it to attract its armature, due to the shunt circuit thereabout, through the corresponding test relay at the selector previously engaged with the terminals of the first trunk. Now in position 2 of the sequence switch, a circuit is completed from battery, through contact 112 (2), armature and back contact of relay J, stop magnet 81, contact 113 (2) and interrupter 125 to ground. Magnet 81 will become momentarily energized, removing the pawl 82 from the ratchet teeth 79 and the brushes will be allowed to return one step into engagement with the next set of contacts. This energization and deenergization of relay 81 will be repeated until brushes 91 engage a contact 87 associated with an idle trunk, when relay J will become energized, breaking the circuit just traced through the stop magnet 81 and stopping the movement of the brushes. The attraction of the armature of relay J also completes the circuit through clutch magnet 101 and stop magnet 102 of the sequence switch 100, whereupon the sequence switch will move into position 3, thus closing at contact 115 (3) and 116 (3), the conductors to the selector brushes 89 and 90. The line will now be extended to the next selector. When the sequence switch 100 passed from position 2 to position 3, it interrupted at contact 103 the holding circuit for the line relay 314, but simultaneously completed a circuit through the right winding of said relay from battery 360, through test brushes 91, contact 107 (3), right winding of relay 314, and contact 106 (3) to ground.

Going back now to the testing process by means of which the trunk consisting of the conductors 303 and 304 was selected, it will be seen that as soon as the master sequence switch 200 reaches position 1, a circuit is closed from battery, through sequence switch contact 211, conductor 166, and all the relays G in series, whereby said relays, becoming energized, attract their armatures, thus removing battery 150 from all the test terminals 312 of the group of trunks being tested. Battery is now supplied to the test contact 312 through the left winding, front contacts and armatures of the relays G, but is of insufficient potential, due to the high resistance of this winding, to cause the ener-

gization of the relay T as the test brush 368 passes over the test contacts 312. These relays will remain energized as long as the master mechanism is in use, but upon its return to normal, the contact 211 will be opened, thus deenergizing the relays G of all the idle trunks. The relays G of the busy trunks, however, will be maintained energized by a circuit from battery, through the left windings of said relays, front contact and armature, test terminals 312, brushes 368, and test relay T of the selector associated with said trunk, this current being sufficient to hold up the armatures of the relays T through the circuit then completed, although it is insufficient to cause their attraction. Thus it will be seen that means are provided which will cause all the trunks of a group to test busy while the master mechanism is employed, and whereby a trunk will test busy at all of its multiple terminals while a selector is associated therewith. When the brush carrier 88 starts to move upwardly, the off normal contact 344 is closed for a purpose to be hereinafter described. When disconnection is desired, the connection of battery 360 to conductors 356 is interrupted and relay 314 becomes deenergized, completing a circuit from battery, through armature and back contact of said relay, sequence switch contact 105 (3), clutch magnet 101 and stop magnet 102 of sequence switch 100, thus moving the sequence switch through position 4 to normal under the control of contact 105. In position 4 a circuit is completed from battery, through contact 111 (4), off normal contact 344, stop magnet 81, contact 113 (4), to ground. Pawl 82 carried by the armature 80 is thus retracted and the brush carrier 88 is returned to its normal position by gravity or in any desired manner. Upon the return of the carriage to normal, the off normal contact 344 is opened, thus interrupting the circuit for the stop relay 81 and completing the last movement necessary to return all the selector apparatus to its normal position.

What I claim is:

- 50 1. In a telephone exchange, a group of connecting circuits, sets of movable contacts in which said circuits terminate, a single motor means for individually moving said sets of contacts, and means whereby all of said connecting circuits will be caused to test busy while said common motor means is in use.
2. In a telephone exchange, a group of connecting circuits, switch brushes in which said circuits terminate, a contact terminal at the opposite end of each of said circuits, a common motor means for moving said brushes, and means whereby all of said cir-

cuit terminals will be caused to test busy while said motor means is in use. 65

3. In a telephone exchange, a group of connecting circuits, switches in which said circuits terminate, a test terminal associated with the other end of each of said circuits, a relay for each test terminal for governing the potential thereof, a motor means for independently moving said switches, and means for actuating all of said relays when said motor means is in use, whereby all the circuits of said group will be caused to 75 test busy.

4. In a telephone exchange, a group of circuits, brushes in which said circuits terminate at one end, a test contact associated with the opposite end of each of said circuits, a relay associated with each test contact for governing the potential thereof, a single motor means for moving said brushes, means whereby all of said relays will be energized while said motor means is in use, 80 85 to cause said circuits to test busy.

5. In a telephone exchange, a group of connecting circuits, switch brushes in which said circuits terminate, a single motor means for independently moving said brushes, 90 means whereby all of said circuits of said group will test busy while said motor means is in use, and whereby each connecting circuit will test busy during the time it is taken for use. 95

6. In a telephone system a group of connecting circuits, switches in which said circuits terminate at one end, a test terminal associated with the opposite ends of said circuits respectively, a relay for each of 100 said test terminals for altering the potential thereof, a motor means common to said switches for independently moving the same, and means for energizing said relays in series while said motor mechanism is in use. 105

7. In a telephone system, a group of connecting circuits, brushes in which said circuits terminate at one end, a test terminal associated with the opposite end of each circuit, a relay associated with each test 110 terminal for governing the potential thereof, a single motor mechanism for independently moving said brushes, means for energizing all of said relays while said motor mechanism is in use, and means for thereafter maintaining energized such of said relays as are associated with the test terminals of busy connecting circuits as long as said circuits are employed. 115

In witness whereof, I hereunto subscribe 120 my name this 15th day of August A. D. 1913.

JOHN N. REYNOLDS.
